UNITED STATES PATENT OFFICE.

JOHN CHEFER, OF CHESTER, PENNSYLVANIA.

TELEPHONE-MOUTHPIECE.

1,375,209.

Specification of Letters Patent. Patented Apr. 19, 1921.

Application filed August 31, 1920. Serial No. 407,076.

To all whom it may concern:

Be it known that I, JOHN CHEFER, a citizen of Belgium, residing at Chester, in the county of Delaware and State of Pennsylvania, have invented a new and useful Telephone-Mouthpiece, of which the following is a specification.

This invention relates to mouthpieces for telephones, one of its objects being to provide a device of this character which can be substituted readily for the ordinary form of mouthpiece and which has means combined therewith whereby the transmission of sound through the mouthpiece can be prevented at will so that while the user of a telephone is in the midst of a telephone conversation, he can cut off the sound to the telephone while carrying on a side conversation momentarily, thus to prevent such conversation being heard over the telephone.

A further object is to provide a device of this character which is simple and compact in construction and which can be manipulated readily.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a front elevation of the mouthpiece.

Fig. 2 is a plan view thereof.

Fig. 3 is an enlarged section on line 3—3,

Fig. 2.

Fig. 4 is a section on line 4—4, Fig. 3.

Fig. 5 is an enlarged section on line 5—5,

Fig. 1.

Fig. 6 is a side elevation of the inner sleeve of the mouthpiece.

Fig. 7 is a section through a portion of the mouthpiece and showing the disk in elevation.

Referring to the figures by characters of reference 1 designates the bell portion of the mouthpiece having a short screw threaded boss 2 provided in its end with diametrically opposed notches 3 and a counterbore 4.

Seated in the counter bore is a disk 5 having

a plurality of apertures 6 therein and provided at diametrically opposed points with projecting lugs 7 and 8 which are seated in the notches 3 so as to hold the disk against rotation relative to the section 1 of the mouthpiece. The ear or lug 8 is longer than the ear 7 and projects slightly beyond the threaded outer surface of the boss 2. A pivot element 9 extends through the center of the disk 5 and engages another disk 10 provided with apertures 11 adapted to register with the apertures 6. This disk rests upon the end of the boss and has a radial ear 12 projecting a short distance beyond the end of the ear 8.

An interiorly screw threaded inner sleeve 12' engages the threaded boss 2 and is provided at one edge with an outstanding flange 13 from which extend prongs 14. A short slot 15 is provided in the ring or sleeve 12' and a notch 16 is formed in one wall of this slot at one end. This ring is adapted to be screwed tightly onto the boss 2 so as to be held against rotation relative to the section 1 and when it is properly positioned the lug 8 will be seated in the notch 16 thus to hold the ring 12' against rotation, while the ear 12 will project into the slot 15 and be capable of a limited movement longitudinally of the slot. This ear 12 projects through the slot 15 and into an opening 17 formed within an intermediate ring 18 mounted for rotation on the ring 12' and having an outwardly extending annular flange 19 at one edge. An annular series of apertures 20 are formed in the intermediate ring 18 and any one of them is adapted to be engaged by a pin 21 carried by a spring 22. This spring is secured to an outer ring 23 which extends around the ring 18 and between the flanges 13 and 19, it being possible by disengaging the pin 21 from the intermediate ring 18, to adjust the outer ring 23 angularly relative to the ring 18 and to then fasten the two rings together. An arm 24 is extended radially from the outer ring 23 and is adapted to work across a segment 25 extending laterally from a ring 26 held between the ring 18 and the flange 13. The back section 27 of the mouthpiece is adapted to be screwed into the inner ring 12' and against the disk 10 after which it can be held against rotation by bending the prongs 14 inwardly into the grooves ordinarily provided in the back portion of a mouthpiece and which have been shown at 28. This

inner section 27 can be screwed into the head of a telephone in the usual manner and it will be obvious that by swinging the arm 24 in one direction the ring 18 will be moved 5 therewith by the pin 21 and as the ear 12 projects into the opening 17, the disk 10 will obviously be moved likewise so as to shift the openings 11 out of register with the openings 6. By moving the arm 24 in 10 the opposite direction, however, the openings can be brought into register. Suitable indications such as the words "off" and "on" can be arranged on the segment 25 to indicate the direction in which the arm is 15 to be moved. By disengaging the pin 21 from the ring 18 the arm 24 can be adjusted angularly to any desired position and then resecured to the ring 18. As the ring 26 is held frictionally, the segment 25 can be 20 easily moved to position where it will be in proper relation to the arm 24.

What is claimed is:-

1. The combination with a mouthpiece section, an apertured disk in engagement 25 therewith and held against rotation thereby, and an inner ring threaded upon said section and held against rotation by the disk, of a second apertured disk pivotally connected to the first named disk, a radial lug thereon 30 having a limited sliding movement within the inner ring, an intermediate ring having an aperture for the reception of said lug and having an annular series of openings, said intermediate ring being revoluble upon 35 the inner ring, an outer ring adjustable angularly upon the intermediate ring, means carried thereby for engagement with any one of the annular series of openings for holding the outer and intermediate rings 40 against relative movement, an operating arm

extending from the outer ring, and an inner mouthpiece section projecting into and secured to the inner ring, said disk being confined between the sections of the mouthpiece.

2. The combination with a mouthpiece 45 section and an apertured disk extending across one end thereof and held against rotation thereby, of an inner ring engaged by said section and held against rotation by the apertured disk, there being a slot within 50 said inner ring, a second apertured disk mounted for rotation on the other disk and having a radial lug slidable within the slot in the inner ring, an intermediate ring engaged by said lug and revoluble upon the 55 inner ring, an outer ring adjustable angularly upon the intermediate ring, a spring held coupling pin carried by the outer ring for engaging the intermediate ring to hold 60 said rings against relative movement, an actuating arm extending from the outer ring, there being annular flanges upon the inner and intermediate rings for holding the outer ring against lateral displacement, a frictionally held ring between the flange of 65 the inner ring and the outer ring, an indicator carried thereby and supported adjacent the arm, and an inner mouthpiece section projecting into and engaging the inner ring and held against rotation thereby, said 70 disk being confined between the two sections of the mouthpiece.

In testimony that I claim the foregoing as my own, I have hereto affixed my signature in the presence of two witnesses.

JOHN CHEFER.

Witnesses:

CHARLES PALMER,
MARIE BRUNHAMER.
